DESIGN.

—o—
J. L. FOLSOM.

CARPET.

No. 18,128.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,128, dated March 6, 1888.

Application filed January 26, 1888. Serial No. 262,050. Term of patent 3½ years.

To all whom it may concern:

Be it known that I, JAMES L. FOLSOM, of Brooklyn, in the county of Kings and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of a number of circular flower forms having concentric rings of radiating leaves, and also smaller bell-shaped flower

forms. These flower forms are all supported upon an underlying stem-work that appears here and there in the intervening spaces. Upon this stem-work, also, are leaves of varying forms and sizes, generally arranged around the flower forms, but sometimes occurring separately between the flower forms. In the open spaces between the leaves and flowers are light stems or twigs.

What I claim as new, and desire to secure by Letters Patent, is—

The design for carpets, consisting of the design substantially as shown.

JAS. L. FOLSOM.
